UNITED STATES PATENT OFFICE

WILHELM RITZERFELD, OF BERLIN, GERMANY

MANIFOLDING MACHINE

Application filed January 8, 1931, Serial No. 507,540, and in Germany September 20, 1928.

The present invention relates to an apparatus for sectionally mainfolding, mainly bookkeeping entries, from an original provided with mirror script (reversed script) 5 on to copy sheets, cards or the like previously moistened with an evanescent coating of a readily volatile liquid (such as methylated spirit, ether or mixtures thereof). Previously known imprinting machines for this purpose, have not been able to be introduced into small and medium sized businesses owing to their expensive structure.

By the apparatus according to the present invention, a machine is produced which is 15 considerably cheaper and, notwithstanding its simple construction, fulfills without objection its intended purpose of effecting book-keeping in small and medium businesses. The apparatus consists essentially of a base- 20 plate on which the sheet, card or the like to be impressed is laid, and of an impressing roller, around which the original provided with mirror script is secured, movably mounted in levers. The impression is ef- 25 fected by depression of the impressing roller on the sheet to be impressed.

A further feature of the subject of the invention consists in the structure of the moistening device. The moistening container is 30 movably and spring mounted in a slide, the slide itself can be displaced by hand along two slide rods secured in the side walls of the machine.

Moreover a contrivance is provided on the 35 impressing roller, by the aid of which after each impression the impressing roller and therewith the original secured thereon can be advanced by the breadth of a line. For this purpose, a ratchet wheel is fast with the 40 impressing roller, in which a pawl spring mounted on the side wall of the machine engages on raising the impressing roller and advances same a given amount correspond- ing to the breadth of a line. By laying back 45 the pawl this contrivance can be rendered inoperative and a line already in position can be impressed as often as required.

In addition a contrivance is provided by 50 the aid of which the original can be adjusted exactly in the impressing position on being

mounted. A mirror adjustable to suit the direction of vision by the operator serves for this purpose. By the aid of this mirror can easily be ascertained even before the beginning of each new operative run, which entry 55 is then about to be impressed.

The sheet or card to be impressed is clamped on the baseplate by means of a clamp.

Constructional examples of the subject of 60 the invention are illustrated on the accompanying drawings, in which:—

Fig. 1 is a front elevation of the apparatus.

Fig. 2 is a side elevation thereof with a side 65 wall removed.

Fig. 3 is a front elevation of a modified apparatus.

Fig. 4 is a side elevation thereof with a side 70 wall removed.

Fig. 5 is a side elevation of the marking 70 contrivance.

Fig. 6 is a view partly in section of the ratchet wheel for advancing the impressing roller together with the original, and also the arrangement of a spring pressed ball for 75 precisely locating the line to be impressed.

Fig. 7 is a side elevation of the moistening device together with the correlated tripping devices, on a larger scale.

Fig. 8 is a rear elevation of the moistening 80 device.

Fig. 9 is a plan of the moistening device.

Fig. 10 is an elevation and

Fig. 11 is a plan of the drive of the moistening device.

Referring more particularly to Figs. 1 and 2, 1 and 2 are side walls held together by a baseplate 3. In the baseplate 3, at the position where the impression is effected, a recess 4 is provided, which serves to receive a 90 counter-pressing strip 5 of elastic material, such as rubber. The original 6 bearing the mirror script is wrapped around a roller 7. The roller 7 is rotatably mounted in two curved levers 8; 9 and 10 are two sheet metal 95 guide plates, which partially cover the roller 7 and are each rockingly mounted in two spring levers 11 and 12 on both sides of the roller-pressing levers 8. In the two guide plates 9 and 10 are mounted guide rollers 13 which 100

provide a sure guidance for the original 6. Keyed on the spindle of the roller is a ratchet wheel 14, in which engages a spring-influenced pawl 16 mounted on a carrier 15 provided on the side wall 2. The two roller-pressing levers 8 are secured on a spindle 17, which can be angularly displaced by a crank 18. The rotation of the crank 18 is limited rearwardly by an abutment stud 19.

10 A moistening container 20 is so mounted in a slide 21, that it can be held in the position shown in Fig. 1 by the action of a spring. The slide 21 slides on two slide rods 22 and 23, and is held in the starting position by a 15 tension member 24 (gut cord or the like), which led over guide sheaves 25 and 26 winds on a spring drum 27. Inside the spring drum 27 is a spiral spring, by the action of which the slide 21 together with the moistening container 20 is constantly drawn back into the 20 position of rest shown. 28 is a spring clamp, by means of which the sheet to be impressed is held firmly on the baseplate 3. This holding device can be raised with the aid of a 25 lever 29.

The mode of operation of the apparatus is as follows:—

In order to be able to pass the original bearing the mirror script conveniently around 30 the roller 7, the two guide plates 9 and 10 are so thrust together that they somewhat overlap and so to a certain extent form a continuous sleeve which covers about half the circumference of the roller 7. By the 35 particular jointed mounting of the guide plates 9 and 10 in the small levers 11 and 12, it results that the plates in the closed together position are somewhat raised from the impression roller. The sheet provided with the 40 original mirror script can then be easily pushed through between the roller and the guide plates. The guides plates are then replaced by hand, whereupon the guide rollers 13 press the original sheet against the roller 7. 45 The sheet to be impressed is so secured on the impression plate by the clamping device 28 that the line to be impressed rests exactly on the elastic strip 5.

The moistening container 20 is then pressed 50 by hand on to the sheet to be impressed and simultaneously drawn over same. Having arrived at the end of the line to receive the impression, the moistening container 20 is released and is drawn back again into the 55 initial position by the action of the spiral spring in the drum 27 with the aid of the tension member 24 (gut cord or the like). The line to receive the impression is now provided with a fine coating of rapidly drying 60 liquid.

With the aid of the crank handle 18, the 65 impressing roller 7 with the original secured thereon is now pressed against the sheet to be impressed. By means of the evanescent moistening, a small quantity of the ink of the

mirror script of the original is dissolved and transferred to the sheet to be impressed. On return of the roller 7, the pawl 16 comes into engagement with the ratchet wheel fast with the roller and turns same onwards an amount corresponding to the distance apart of the lines of the original, so that the next line comes into the impressing position.

A mirror 30 let into the baseplate, enable the correct position for impressing to be at 75 once found on mounting the original and to determine the entry now come to be impressed before the commencement of each new operative run.

In the above described apparatus the various operation, such as moistening, impressing, opening and closing of the card clamp are individually successively effected by different separate actuators. The apparatus can however be so constructed that the several operations are effected in a single operation in an interdependent manner by actuation of a handle, lever or the like.

The card clamp in such case is automatically opened and closed by the rocking of 90 the levers carrying the impressing roller.

On depression of the impressing roller the moistening device is simultaneously drawn over the sheet to be impressed in such manner that the moistening of the sheet is terminated before the impressing roller with the line to be impressed reaches the moistened section of the card to receive the impression. On the outer side of one of the side walls of the apparatus there is for this purpose a cord drum, on which the tension members, which lead over the sheaves to the moistening device, are wound in opposite rotational directions. This cord drum is connected by spurwheels with the spindle on 100 which the curved levers of the impressing roller are mounted, so that, on rocking on the impressing roller, it is rotated by such spurwheels and thus draws the moistening container over the card to receive the impression. On return of the impressing roller the cord drum rotates in the reverse direction and the moistening container is drawn back again 110 into the initial position.

On the guide bar along which the moistening device slides, tripping devices are provided, which on the commencement of the moistening operation lower the moistening device on to the sheet to receive the impression and after completed moistening raise it again automatically from the now moistened card. These tripping devices can be adjusted along the guide bar, so that cards of different widths can be moistened. In its initial position the moistening container projects with its lower protruding felt filling into an intermediate container, secured to the side wall and provided with a notch, which is likewise filled with absorptive material and is saturated with readily volatile liquid from 120 125 130

a reservoir container (a drop feed vessel ground spirit-tight) arranged above. Thus, the filling of the moistener which wipes over the card sucks up liquid anew after each 5 moistening excursion.

The device for advancing the impressing roller with the original secured thereon, the breadth of a line can be improved by the impressing roller being connected by an adjustable cone with the ratchet wheel, in which the spring-pressed pawl pivoted behind same engages on raising the impressing roller, and advances same a given amount corresponding to the breadth of a line. The cone can be drawn back by a small lever, so that the advance of the impressing roller is suspended and the line adjusted in position can be impressed several times in succession. This contrivance is also of importance for the adjustment of the line of the original to be impressed, because with the cone withdrawn the impressing roller permits itself to be easily turned in its bearings, without the ratchet wheel rotating therewith.

In order to ensure exact advance of the original from line to line, an indicator is provided in the form of a spring-pressed ball which from line to line snaps into recesses provided therefor in and for each tooth of the ratchet wheel and prevents inadvertent further movement of the impressing roller with the original stretched thereon, so that the lines to be impressed always positively arrive in the impressing position.

The impressing roller itself can be provided with a pressing bar over which the original provided with mirror script capable of imparting impressions is looped. This pressing bar serves the purpose of ensuring a completely uniform pressing together of the line of the original to be impressed with the card or the like to receive the impression resting on the elastic base.

Moreover, on the levers or the like carrying the impressing roller, a movable paper support can be provided which prevents the original hanging down behind and smudging the original script.

In order to ensure that the impressing roller, in whatever position it may be, always assumes the same condition, i. e. the pressing bar and thereby the line of the original to be impressed always is on the underside, the impressing roller can be rotatably mounted in bearer levers, which are pivotally connected to curved pressing levers fast on a spindle, whereby parallel guidance is effected. As the line to be impressed is in such case constantly directed downwards, the mirror is then arranged beneath the impressing roller.

In order to have a control as to whether and how often each line of the original is impressed, a marking device is provided on the machine, by means of which each line im-

pressed is made known by an ink mark or the like. This marking device is laterally adjustable in order that a line impressed several times can be marked in a different place for each impression.

The above described modifications of the subject of the invention are illustrated in Figs. 3 to 10. In these figures: 1 and 2 are side walls held together by a baseplate 3. In the baseplate 3, at the position where the impression is effected, a recess is provided, which serves to receive the counter-pressing strip 5 of elastic material, such as rubber. The original 6 bearing the mirror script is wrapped around the impressing roller 7. On the underside of the impressing roller 7 a pressing bar 7¹ is provided, which is secured to two carrying levers 64 and therefore does not rotate with the roller 7. This pressing bar 7¹ has the purpose of ensuring completely uniform pressing together of the line of the original to be impressed and the card or the like which is to receive the impression and which rests on the elastic counter-pressing strip 5.

The sheet metal guide plates 9 and 10, with the guide rollers 13 press the original against the impressing roller 7. On the two roller-carrying levers 64, a paper support 66 of wire, sheet metal or the like is movably attached, on which rests the original hanging down behind the impressing roller, so that it cannot drag along the baseplate 3, whereby the mirror script capable of impressing might smudge. The ratchet wheel 14 is connected to the spindle of the impressing roller by a cone 62, which by means of a hand lever 63 alternatively can be either loosened or forced into the boss of the ratchet wheel 14, in order to couple same to the roller 7. The roller-carrying levers 64 are pivotally connected to the two curved pressing levers 8 and 8¹. The pressing lever 8¹ is prolonged into a handle 18, by means of which the entire apparatus can be operated. The impressing roller 7 is journalled in the roller-carrying levers 64, which are pivoted at their rear ends to parallel guide levers 65, which in turn are pivotally mounted on pedestal bearings on the counter-pressing plate 3. A parallel guidance of the impressing roller is thus provided, i. e. the impressing roller always assumes the same angular situation in whatever position it may be, the pressing bar and the line to be impressed always pointing downwards. Underneath the impressing roller 7 is arranged a mirror 67, in which the line of the original for the time being on the pressing bar 7¹ is visible in correctly reading script, so that the impression of the correct line and the adjustment of such line in the correct impressing position can be controlled.

The card to receive the impression is clamped firmly on the baseplate 3 by a card clamp 45. On raising the impressing roller

7, a boss 46, on each of the pressing levers 8 and 8¹, presses on a stem 47 extending through the baseplate 3, and which is pivotally connected to one arm of a lever 48 pivoted 5 beneath the baseplate 3. The other arm of this lever 48 is connected to a stem 49, which on depression of the stem 47 by the boss 46, raises the card clamp 45, so that the card to receive the impression is freed for being 10 changed or displaced.

Between the side walls 1 and 2 there is a profiled rail 22 on which the moistener carriage 21 runs by means of rollers. The moistener 20 is pivotally mounted on the 15 moistener carriage 21. The moistener 20 projects in the position of rest with its downwardly protruding felt or wick 20' filling into a notch of an intermediate container 21¹, which is connected to a reservoir vessel 21¹¹ 20 and likewise is filled with absorptive material (felt, cotton wool or the like). From the moistener carriage lead tension members 34 (gut cords or the like), which are secured to both sides of the moistener carriage 21, 25 over sheaves 36 to a two-part cord drum 35, on which these tension members are wound in opposite directions. The cord drum 35 is connected by a train of spur-wheels to the spindle 17 on which the pressing levers 8 30 and 8¹ are fast. As shown in Fig. 10, the spur-wheel 37 keyed on the spindle 17 is not toothed throughout its entire periphery, but has a slipping surface 38, which corresponds with a slipping surface 40 on a spur-wheel 39. 35 The two spur-wheels 37 and 39 are so mutually set, that when the impressing roller is depressed and the moistening container is in its outermost position against the side wall 2, the transmission of rotation ceases, because 40 at such instant the slipping surface 38 and 40 interact. Only on raising the impressing roller 7 do the spurwheels 37 and 39 again come into mesh, and the moistener carriage travels back to its initial position only then 45 when the impressing roller 7 can no longer obstruct it.

From the spur-wheel 39 the rotation of the spindle 17 is transmitted in the usual manner by spur-wheels 41 and 42 to the cord drum 35. 50 The cord drum 35 is of two-part construction, the two individual drums of which are united by screws 44. As the screws 44 extend through slots 43 in the outer drum of the cord drum 35, the relative positions of the two 55 individual drums can be varied within limits after loosening the screws 44, in order thereby to adjust the tension of the tension members 34.

The moistening container 20 automatically 60 applies itself to the card to receive the impression and on terminated moistening is automatically raised from the card. For this purpose trip devices are adjustably arranged on the guide rail 22 and which serve both for 65 applying the moistener and also for raising

same, for enabling cards of different width to be moistened and impressed. Fast with the moistening container is an eccentric cam disc 23, Fig. 8, over which engages, in the raised condition of the moistener 20, a spring-influenced detent 24 which is provided on the upper surface of the moistener carriage 21, and which prevents the moistener 20, which is spring-drawn downwards, from applying itself to the counter-pressing strip 5 in advance of the card to receive the impression. Only when the moistener carriage has reached the card to receive the impression, is the spring-influenced detent 24 released by a trip pawl 32, which is provided on a trip release device 31, and the moistener 20 applies itself 70 yieldingly to the sheet to receive the impression and moistens same in the course of its further movement. The trip release device is clamped in the adjusted position along the 75 guide rail 22 by a screw provided with a lever 33. When the moistening of the card to receive the impression has terminated, a release pawl 26, pivotally mounted on a lever 25 connected to the moistener 20, encounters an abutment 29 on a raising trip device 27, whereby the moistener 20 is raised. At the same instant the eccentric cam disc 23 frees the spring-influenced detent 24, and this now 80 bolts the moistener 20 in the raised position. The raising trip device 27 can likewise be clamped fast at any desired position along the guide rail 22 by a screw provided with a lever 30. During the return movement of the 85 moistener carriage 21 the pawls 26 and 32 resiliently yield to the corresponding abutments, so that thus the moistener 20 remains in the raised position. 90

The line to be impressed on the original is provided with a distinguishing mark at each 105 impression, so that there is a control as to whether and how often each line is impressed. In the side wall, 1, a spindle 50 is mounted on which a bearing block 51 is displaceably and securably mounted. A stem 52 is guided in the bearing block 51, and carries at its upper end a printing type 53 and at its lower end is pivotally connected to one arm of a rocking lever 54. On the other arm of the 110 lever 54 is a rearwardly yielding pawl 55, against which, on raising the impressing roller 7, strikes an abutment 56 provided on the spindle 17 and thereby so rocks the lever 54 that the type stem 52 presses the type 115 53 against the line on the pressing bar 7¹ 120 just impressed. A tension spring 54¹ is connected to the lever 54 and after each marking draws the lever 54 and thereby the type stem 52 downwards. An inking pad 57 is mounted on the bearing block 51 above the type 125 53, and is pressed by a spring 57¹ against the type 53. The carrier of the inking pad 57 has a lug 58. On the type stem 52 is a projection 59 which on ascent of the type stem 130 presses against the lug 58 on the inking pad

carrier and thereby rocks the inking pad, so that the type stem can unhindered reach the impressed line of the original.

The mode of operation of the above described apparatus is briefly as follows:

The original for imparting impressions is applied to the roller 7 with the mirror script side outwards and the line to be impressed so adjusted that it rests against the pressing bar 10 71. The card to receive the impression is so slid beneath the then open card clamp 45, that the line which is to receive the impression comes to rest on the elastic counter-pressing strip. The handle 18 is then pressed 15 down. Before the impressing roller 7 has reached the card to receive the impression, the moistening container 20, after having yieldingly applied itself, by virtue of the release trip device, against the card to receive 20 the impression, has passed along same. The impressing roller 7 then reaches the moistened card and the impression is effected. During the now following raising 25 of the handle 18, the moistener container 20 travels back in the raised condition to the initial position, the marking device is actuated and provides the just impressed line on the original with a distinguishing mark and simultaneously the card clamp 45 is 30 again opened and the original is advanced by a line. The impressed card can now be exchanged or another line on the same card can be brought into the impressing position, whereupon the operations described are 35 repeated.

By the provision of several adjustable release- and raising-trip devices, the card to receive the impression can be moistened at discontinuous positions along a line so as to 40 receive impressions at given pre-determined positions.

Having now particularly described and ascertained the nature of my said invention and in what manner the same is to be performed, I declare that what I claim is:—

1. A machine of the class described comprising a base plate, levers pivotally connected with the base plate and having a paper feed roller journalled thereon, guide plates 50 yieldably connected with the roller for holding a copy sheet thereon, and means for detachably securing a card upon the base plate for receiving an impression from the copy sheet, means movable transversely of the base plate for moistening the card, and means for swinging the levers to move the roller and copy sheet into engagement with the card.

2. A machine as claimed in claim 1, where- 60 in the guide plates of the roller are yieldably interconnected.

3. A machine as claimed in claim 1, where- 65 in the feed roller is provided with a ratchet wheel, a pawl pivotally connected with the base plate for engaging the ratchet wheel

when the roller is swung in one direction to impart a step by step movement to the roller.

4. A machine of the class described comprising a base plate, a pair of levers pivotally connected therewith, a paper feed roller 70 journalled on the levers, means for guiding a copy sheet around the roller, a copy impression card detachably connected with the base plate, a liquid container slidably guided transversely of the base plate and having a wick for applying moisture to a part of the card, and means for swinging the levers, and thus the roller with the copy sheet upon the moistened part of the card.

5. A machine as claimed in claim 4 where- 80 in the liquid container is slid in one direction as the roller is swung downwardly and in a reverse direction when the roller is swung reversely.

6. A machine of the class described comprising a base plate, a paper feeding roller 85 swingably connected with the base plate, a copy impression card upon the base plate, a moistening device, means operable upon swinging the roller to move the moistening device into engagement with the card and to move the same transversely thereon when the roller is swung downwardly, and means operable upon swinging of the roller upwardly 90 to lift the moistening device and move it in a reverse direction.

7. A machine of the class described comprising a base plate, a copy sheet feed roller pivotally connected with the base, means for clamping a card on the base plate to receive an impression of the copy on said sheet, a guide rail supported above the base plate, a moistening device slideable on the rail for applying moisture to the card when the moistening device is moved in one direction, a gear train, a drum rotatable by the gear train, flexible connections between the drum and moistening device for imparting movement thereto in one direction to apply moisture to the card when the roller is swung in a direction to engage the card and in a reverse direction when the roller is swung from engagement with the card.

8. A machine of the class described comprising a base plate, a copy sheet feed roller pivotally connected therewith and swingable to impress copy thereon upon a card upon the base plate, a moistening device including a wick, a liquid container on the base in which the wick is normally immersed, means operable upon swinging the roller in one direction for lifting the moistening device and its wick from the container and to slide the wick across a part of the card previous to the engagement of the roller therewith, said means also being operable to move the moistener in a reverse direction upon swinging the roller reversely.

9. A machine as claimed in claim 1 where-

85

90

95

100

105

110

115

120

125

130

in the guide plates have mounted thereon rollers.

10. A machine as claimed in claim 1 wherein the guide plates when moved towards each other simultaneously move away from the roller to position their longitudinal edges in overlapped relationship.

11. A machine as claimed in claim 1 wherein the base plates have non-rotatably mounted therein a strip upon which the copy sheet is pressed when subjected to the pressure of the roller.

12. A machine as claimed in claim 7 wherein means are slidably mounted on the guide rail for moving the moistening device into and out of engagement with the card.

13. A machine as claimed in claim 1 wherein the card securing means is opened or closed during swinging of the roller.

20 14. A machine as claimed in claim 1 wherein means are provided for marking each impressed line of the sheet.

15 15. A machine as claimed in claim 1 wherein a mirror is mounted on the base plate.

25 16. A machine as claimed in claim 1 wherein there is mounted below the feed roller a pressing bar on which the copy sheet is adapted to bear, said bar being non-rotatably mounted with respect to the roller.

In testimony whereof I have affixed my signature.

WILHELM RITZERFELD.
